UNITED STATES PATENT OFFICE.

MATTHEW W. RYAN, OF NEW YORK, N. Y.

DESIGN FOR A CRETONNE OR OTHER TEXTILE FABRIC.

50,760.

Specification for Design.

Patented May 8, 1917.

Application filed January 30, 1917. Serial No. 145,533. Term of patent 3½ years.

To all whom it may concern:

Be it known that I, MATTHEW W. RYAN, a citizen of the United States, residing in the city of New York, borough of Manhattan, in the county and State of New York, have invented a new, original, and ornamental Design for a Cretonne or other Textile Fabric, of which the following is a specification, reference being had to the accompanying drawings, forming a part thereof.

The figure is a plan view of a portion of a cretonne or other textile fabric showing a full repeat of my design.

I claim:

The ornamental design for a cretonne or other textile fabric consisting of the design substantially as shown.

MATTHEW W. RYAN.
